Howe & Horren

UNITED STATES PATENT OFFICE.

FRANK S. BENNETT, OF PHILADELPHIA, PENNSYLVANIA.

INNER-TUBE COVERING FOR TIRES.

1,346,632.

Specification of Letters Patent. Patented July 13, 1920.

Application filed October 11, 1919. Serial No. 330,070.

To all whom it may concern:

Be it known that I, FRANK S. BENNETT, a citizen of the United States, residing in Philadelphia, Pennsylvania, have invented 5 certain Improvements in Inner-Tube Coverings for Tires, of which the following is a specification.

The object of my invention is to prevent chafing of the inner tube of an automobile 10 tire by the action of small pebbles, or stones, that work their way into the space between the shoe of the tire and the inner tube, and also by the rubbing of the shoe against the inner tube. My invention also prevents the 15 adhering of the inner tube to the shoe.

In the accompanying drawings:

Figure 1 is a perspective view, showing a deflated inner tube with the cover thereon;

Fig. 2 is a perspective sectional view, 20 showing the shoe of an automobile tire, the inner tube and the protecting covering, and

Fig. 3 is a view illustrating a modification of the means for fastening the edges of the cover together.

Referring to the drawings, 1 is an ordinary shoe of an automobile tire. 2 is the inner tube having a valve stem 3 of the usual type. 4 is a covering for the inner tube, which is endless, the two ends of the tube 30 being secured together at 5, in the present instance, by stitching. The tube is preferably made of a ribbed, knitted fabric in which the ribs run longitudinally of the tube, so as to allow it to yield laterally when 35 the inner tube is expanded. At each edge of the covering is a binder 6 of woven fabric, held to the covering by stitching. At one edge is a flap 7, which passes under the outer edge. The two edges are held together by 40 any suitable fastenings.

In Fig. 2, I have illustrated snap fastenings 8, arranged at intervals, but it will be understood that buttons may be used, or the two edges may be laced together, as shown 45 in Fig. 3. The two binders 6^a have eyelet holes 9 spaced a given distance apart and a lacing 10 is introduced so as to draw the two edges together, as shown in said figure. Other suitable means may be provided for 50 securing the edges of the covering together.

It will be understood that the fabric is preferably knitted so as to allow it to expand freely to accommodate the action of the tire when in service. It will be understood 55 that it may be of any thickness desired.

I find that by the use of this covering any small particles, pebbles, or stones, which work their way between the inner tube and the casing, will not chafe, or bruise, the inner tube, as they will become embedded in the fabric of the covering and held therein, the thickness of the covering preventing the pebbles, or other small particles, from attacking the inner tube. 60

Furthermore, the covering prevents the inner tube adhering to the outer casing, which often occurs when there is not sufficient powdered substance between the two. I find that very little powdered material is 70 required. In some instances I have found that the powdered material can be dispensed with, when the covering is used.

In some types of tires, a piece of fabric is secured to one side of the shoe so as to extend 75 over the opening to prevent dust from entering this open space, but by the use of the covering, as shown, this piece of fabric may be dispensed with.

I find, in practice, that the material of the 80 tube does not show appreciable wear when used in long service, and it protects the inner tube. The majority of blowouts of the inner tube are caused by small pebbles working their way into the surface of the tube 85 and weakening it at that point so that, when the tire strikes an obstruction, this weakened portion of the tube gives way and a blowout occurs.

In some instances, two or more thicknesses 90 of fabric may be used when it is desired to have a thick body of fabric between the shoe and the inner tube.

I claim:

1. As a new article of manufacture, a 95 strip of fabric adapted to be folded so as to detachably envelop an inner tube of an inflatable tire, said strip being composed of a close-mesh, knitted textile fabric having the property of embedding foreign particles 100 which may enter between the tube and its carcass or shoe, and reducing friction between said tube and shoe, and co-acting fastenings along the meeting edges of said strip. 105

2. As a new article of manufacture, a strip of fabric adapted to be folded so as to detachably envelop an inner tube of an inflatable tire, said strip being composed of a close-mesh, knitted textile fabric having the 110 property of embedding foreign particles which may enter between said tube and its

carcass or shoe, and reducing friction between said tube and shoe, and co-acting fastenings along the meeting edges of said strip, said strip having a binder along its 5 edges, one of said edges having a flap to underlie the other edge.

3. As a new article of manufacture, an auto tire sock formed of a strip of fabric adapted to be folded so as to detachably envelop an inner tube of an inflatable tire, said

strip being composed of a close-mesh, knitted textile fabric having the property of embedding foreign particles which may enter between the tube and its carcass or shoe, and reducing friction between said tube and 15 shoe, said strip consisting of two or more thicknesses of material, and co-acting fastenings along the meeting edges of said strip.

FRANK S. BENNETT.
